INDUCTION HEATING APPARATUS

Harold A. Strickland, Jr., Detroit, Mich., assignor, by mesne assignments, to The Budd Company, Philadelphia, Pa., a corporation of Pennsylvania

Application September 2, 1943, Serial No. 500,903

16 Claims. (Cl. 219—13)

1

This invention relates to induction heating apparatus. More particularly the invention relates to heating apparatus provided with mechanism adapted for holding workpieces of varying lengths including an extreme length beyond that of the furnace casing.

In induction heating apparatus such for example as described in my co-pending application, Serial No. 384,503, filed March 21, 1941, use is made of an induction heating coil within which a workpiece is inserted, the feed opening of the heating coil being normally closed in the heating cycle by a pivoted hood which functions to initiate the heating operation and also to prevent access for removal of the workpiece while the heating current is effective. This is of importance in order to protect the workmen from possible electrical breakdown and shock and also to prevent removal and re-insertion of the workpiece during the continuance of the heating cycle. A disadvantage of this construction resides in the fact that the furnace cannot operate with a workpiece of such length that a portion thereof extends outwardly beyond the hood thus preventing closing of the hood and the initiation of the heating action.

One of the primary objects of the present invention is to provide a holding or electrical grounding device and closure means for a workpiece in an induction heating coil furnace which is effective to clamp a workpiece of extreme length without interfering with the normal heating function of the apparatus. Another important object is to provide means for clamping a long workpiece in the apparatus which also provides a ground in case the workpiece should be removed during the heating cycle. Still another object is to provide a clamping means for workpieces, which is automatically adjustable to workpieces of different diameter. Still another object is to provide a clamping means for a workpiece which in the case of a short workpiece moves to close the feed opening to prevent removal of or contact with the piece while heating is in progress. An additional object is to provide a clamping or closure means for a heating coil which functions in time sequence in relation to the means for initiating the heating cycle. Additional objects are to provide a holding means for a workpiece in an induction furnace which functions normally in conjunction with the means for initiating the heating cycle but which may function independently thereof without disturbance of the cycle initiating means; to provide means for closing a relay circuit simultaneously with the

2

closure means for the feed opening, but capable of independent movement of said closure means; and to provide simplified construction for the operation of the induction heating apparatus.

5 Other objects will appear on examination of the following description of the invention taken with the accompanying drawings, in which:

Fig. 1 is a side elevation of the upper portion of the heating apparatus showing the furnace casing and associated control apparatus;

10 Fig. 2 is a front elevational view showing the feed opening closure mechanism, partly in section;

Fig. 3 is a vertical section taken through the 15 control box showing the means for initiating the heating cycle;

Fig. 4 is a vertical section taken along the lines

4—4 of Fig. 3;

Fig. 5 is a horizontal section taken just below 20 the top casing wall of Figs. 3 and 4 and illustrating the control mechanism;

Fig. 6 is a detail showing the relationship of 25 workpiece and holding means at the front opening or mouth of the furnace;

Fig. 7 is a section along the lines 1—7 of Fig. 6, and

Fig. 8 is a wiring diagram of the electric circuit.

Referring to Fig. 1, I have shown in outline 30 an electrical induction heating apparatus having particular adaption to the heating of bars or the like. The construction of the apparatus is in general similar to that shown in my co-pending application above referred to and includes three sections, the numeral 10 being applied to the furnace section proper, the numeral 11 to the section including the control mechanism and the numeral 12 to the section containing condensers and bus bar connections.

40 The furnace section 10 is provided with a casing 13 and a front end plate 14 within which is shown in dash outline the base plate 15 supporting C-brackets 16 the latter in turn supporting the induction heating coil unit 17. The feed 45 opening or mouth 18 formed in a plate 6 attached to the end plate 14 is in extension of the heating chamber 19 of the heating coil and within this chamber and extending outwardly beyond the feed opening is a workpiece 20. Feed 50 opening guide ring 21 functions to assist in the support of the workpiece 20 as well as to aid in guiding the workpiece into the end of the coil, as described in my co-pending application Serial No. 506,016, filed October 13, 1943, now Patent No. 2,400,660, dated May 21, 1946.

Means for grounding the workpiece or alternately for preventing removal thereof where the workpiece is of such a length as to be included within the casing, is illustrated particularly in Figure 2 of the drawings. In this figure there is shown in horizontal alignment with the center of the workpiece 20 and on either side of the same, clamping mechanisms 22 and 23, each consisting of a cylinder 24 secured by bolts 25 to the outer face of the end plate 14. These cylinders are each provided with pistons 26 having projecting piston rods 27, the pistons normally being urged outwardly in relation to the workpiece by coil springs 28. The inner ends of the piston rods terminate in lateral yokes 29 having pivot rods 30 on which are mounted rollers 31 forming the clamping or closure elements for the workpiece. Rollers are required because of axial expansion of the workpiece while heating. In operation, when pressure is led into the cylinder chamber, as by pipe lines 32, the pistons are moved inwardly, carrying the holding elements 31 into engagement with the workpiece 20 if extending through the feed opening of the furnace, the pressure of the pistons being such as to maintain the rollers fixedly in position against the workpiece, effectively grounding the same through the all-metal structure of the machine frame. In the case of a workpiece included entirely within the furnace casing, the contact rollers move into close position with each other and present an effective barrier against removal or contact with a workpiece. Cross guide plates 33 are welded to the inner edges of the yokes 29 to prevent rotation of the roller suspensions on the otherwise rotatable piston rods, as well as for supplementation of the rollers in coacting as a barrier for the feed opening.

Control apparatus for initiating the movement of the holding or closure means 31 as hereinabove described is shown in detail in Figures 3 through 6, and is referred to generally by the numeral 35. This unit is enclosed in a casing 36 attached by adjustable screw bolts 5 to the end plate 14 above and to one side of the feed opening of the workpiece and heating coil and directly above the pressure cylinder 23 as shown in Fig. 2. The casing 36 is box-shaped and is provided on its outer face 37 with enlarged spaced openings 38 and 39, one above the other. Within the casing 36 and fixed to the end plate 14 is a base plate 40 to which at the upper end thereof is fixed a three-way valve unit 41 extending horizontally from the base plate 40 through the opening 38 in the control casing and terminating in a push button 42 whereby the valve is operated.

The three-way valve structure is shown more clearly in Fig. 5, the valve comprising a casing 43 having an exhaust port 44, and inlet port 45, and an outlet port 46. The inlet port is coupled to an inlet pressure conduit 47 and the outlet port, through a conduit 48, to the pipe line 32 associated with the pressure units 22 and 23. Within the casing 43 of the valve adjacent the inlet port 45 is a chamber 49 in which a freely floating valve member 50 is adapted to have axial movement. This valve member is formed as a circular plate 51 with axially extending edges 52 forming depressions on either side of the plate 51, the end of the plate adjacent the base 40 forming a recess for a coil spring 53 which normally urges the valve member 50 axially against the other side 54 of chamber 49. The other recess of the valve member 50 holds a soft rubber plate 55.

Adapted for axial movement also within the casing 43 is the valve rod 56 which is axially hollowed at the end adjacent the valve member 50 to form a channel 57 extending from the free end of the rod 56 to a point 58 where a lateral duct opens from the rod into a transverse duct 59 formed in a stationary member 60 within which the rod 56 is movable and communicating with the exhaust 44. A chamber 61 separates the rubber plate of member 50 and the end of the valve rod 56, said chamber communicating with the outlet port 46. Within this chamber also is a coil spring 62 surrounding the end of the valve rod for retaining the packing in place as shown in Figure 5. In this position fluid under pressure in the clamping mechanisms 22 and 23 will have free exit through the conduits 32 and 48, chamber 61 and duct 57 to the exhaust port 44, thus relieving the pressure in the cylinders 24 of the holding units and permitting movement of the holding member away from the workpiece.

In Figures 4 and 5 the adaptation of the valve means is shown for use in connection with the operation of electric switches 124 and 125. These switches are included in the casings 63 and 64 and utilize spring operating plates 65 and 66. These spring plates, as shown, are fastened by screws to the switch casings and hence are freely movable to operate switch plungers intermediate the spring plates and the casings 63 or 64. The free ends of these spring plates underlie the annular flange 67 formed on the inner end of the hollow push button 62, so that axial movement of the push button causes movement of the spring members and consequent actuation of the switches within the casings 63 and 64. In order to secure this switch actuation to some degree independently of the actuation of the three-way valve, the push button is slidably mounted on the end of an extension of the valve casing 43, so as to have a limited sliding movement relative to the valve casing before engaging the valve rod 56 when moved toward the rod. To this end the tubular casing 68 is screw threaded within the push button head, this casing extending to and having slidable engagement with the outer end 69 of a coupling 70 screw threaded to the valve casing 43. The inner end of this tube 68 is closed by an inwardly extending annular flange except for a central aperture within which the stem of a headed member 71 placed within the tube 68 is movable. A coil spring 72 is positioned within the casing 69 which normally urges the headed member 71 into the extreme inward limit of movement with sufficient initial pressure so that the spring is compressed further only after the valve rod 56 is pressed against its rubber seat 55. The protruded stem of the member 71 is normally adjacent but out of contact with the outer end of the valve rod 56. The guiding collar 73 on the valve rod 56 holds the end of the valve rod in position and also provides a seat for the inner and outer coil springs 74 and 75 whereby the head and the attached valve stem are normally urged to outward position and packing is pressed around the valve rod 56.

The periphery of the annular flange 67 is inclined toward the axis of the valve in a direction away from the cap of the button to form a camming surface 76. Adapted to cooperatively engage this camming surface is a similar surface formed on the member 77 mounted on the pivot pin 78, supported beneath the extension casing 70 of the valve. In operative position of the mechanism the camming surface of the member

77 engages the camming surface of the flange 67 and is held in this position by means of a coil pivot spring 79. It now appears that when pressure is applied to the push button 42 the initial action will be to force the pivotal member 77 downwardly until the cam surfaces override each other, whereupon the spring 79 will force up the pivotal member, so that its end engages the edge of the flange 67 thereby holding the push button in a predetermined fixed position inwardly of its normal inoperative position. The push button is maintained in this inward position until the pivotal member is forced outwardly to such an extent as to permit the flange of the push button to escape from the detent and move to its normal outer limit. The means for releasing the push button and its movement of the pivotal member 77 comprises the lever arm 80 pivotally mounted on the pivot 78 and extending between the member 77 and the extension valve casing 70. On the opposite side of the pivot from the lever 80, the arm 81, integral with the lever, extends and terminates in a pivot pin 82 to which side plates 83 are attached extending freely downwardly to engage the cross pin 84 at the base thereof, thus forming a square-shaped pendent frame. Within this frame and secured to the base plate 40 is an electro-magnet 8 having an armature 85 movable therein in an approximately vertical direction, the outer end of the armature terminating in the double arch-shaped member 87 having apertures adapted to receive the cross pin 84. Spacing tubes 88 are placed on said cross pin intermediate the member 87 and the depending side plates 83 to hold the frame in fixed relationship to said member. With this construction, on energization of the electro-magnet, the attraction of the member 87 results in an upward movement of the same. The frame is lifted thereby operating the arm 81 and causing the lever 80 to press the pivot member downwardly thereby releasing the push button from its inwardly placed position.

An alternative manual means for operating the lever 80 is also provided in a second arm 90 fixed to the arm 81 and extending generally downwardly therefrom and toward the front side 37 of the control casing 36. The end of this arm terminates in a contact plate 91 adjacent the aperture 39 in the lower side of the front control plate 37. Extending rearwardly from the sides of the opening 39 is guide casing 92 having an inner wall formed with a central aperture. Movable within this aperture is a plunger 93 having a finger plate 94 and an end stop 95 attached to the plunger external to the inward aperture thereof. A spring 96 is coiled around the plunger within the guide casing 92 between the finger plate 94 and the inner edge of the plunger receiving aperture. The action of this spring is to normally maintain the finger plate at the outer limit of its movement but to permit yieldable inward movement of the finger plate whereby the end of the plunger is moved against the contact plate 91 of the lever 90 and thus moves the lever arm 80 downwardly to cause release of the push button.

On reference to Fig. 5 it will be observed that the connections from the outlet 46 through the pipe line 48 terminates in a coupling 97, one end of which is connected to the pipe 98 leading into the clamping pipe line 32 (Fig. 2) and the other end connected into the pipe line 99 having connection to a pressure operated switch 184 shown in Fig. 4. This switch is adapted for actuation whenever pressure is applied to the holding cylin-

ders 24, so that this switch and the holding mechanisms are directly related and act simultaneously. Similarly on release of the pressure in the holding cylinders the pressure switch is operated to open and break the circuit.

Terminal bar 100 mounted on angle plates 104 is also positioned within the casing and attached through the angle plates to the base plate 40.

The wiring diagram of the heating apparatus is shown in Fig. 8 the power source supplying alternating current being indicated at 110, and the main circuit lines at 111 and 112. The circuits may be roughly classified in five sections designated as "Supply," "Starting," "Load safety," "Timer" and "High frequency" and identified as in the drawings as A, B, C, D and E respectively. The supply section A includes fuses 113, overload disconnection heating elements 114, and main switches 115. Included also are the main power line 60 cycle pilot lamp 116, water pressure switches 117, water pressure pilot lamp 118, water heater 119, and water thermostat 120. Main lines 111 and 112 extend from the supply circuit A into the starting and load protective circuits B and C, these two sections being mutually dependent for operation. Starting circuit B is based on a pilot contactor relay 121 which on energization is adapted to close the contacts of switches 122 and 123. In addition to the basic elements mentioned, the starting circuit includes the starter switches 124 and 125, pilot lamp 126 and main contactor relay switch 127, the circuit passing from main line 112 through tap line 128, pilot lamp 126 and relay 121 in parallel, main relay switch 127, pilot contactor relay switch 123 and starter switch 124 in parallel, and starter switch 125 to the load safety section C. Also from starter and pilot relay switches 123 and 124 a branch line leads through pilot relay 122 to a sequence or distributor switch 148, which selects the particular furnace of a bank of furnaces for energization, and thence to the timer circuit section D.

The basic elements of the load-safety section C are the anti-reset relay 129 and load switch contact elements 8a, 8b and 101a, 101b. Anti-reset relay 129 is adapted on energization to close anti-reset relay switches 131 and 132.

In addition to the enumerated basic elements, there is included in the C section the anti-reset pilot lamp 136, and water temperature and flow switches 140 and 141. The circuit leads from main line 111 through water temperature and flow switches 140 and 141, load switch contact elements 8a and 101a in parallel, through anti-reset relay switch 132, junction point 144, to hood switch 125 of the B section. Also from main line 112 the circuit leads through the anti-reset relay coil 129 and pilot lamp 136 in parallel to a common junction 142; thence by anti-reset relay switch 131 to a common junction point 143. From point 143 the circuit leads through switch contact elements 101b and 8b to point 142. Switch contact elements 101b and 8b are normally closed, and switch contact elements 8a and 101a normally open.

The timer current section D is formed principally of two timers of any appropriate commercial make together with related elements. The function of the timer is to effect a timer limit, subject to adjustment, on the amount of heat received by the workpiece and two timers are used to insure completion of a heating cycle in case one timer should fail to perform properly. Timer 150 includes the timer solenoid 151, motor

152 and magnetic timer lock switch 153. Associated with this timer are the timer on-relay 154 and timer on-relay switch 155. A switch arm 156 is movable to "on" position at switch contact element 157 and to "off" position at switch contact element 158. Similarly in timer 160 is included the solenoid 161, motor 162, and magnetic lock switch 163. Associated with this timer 160 are timer on-relay 164, timer on-relay switch 165 and a switch arm 166 movable to "on" position contact element at 167 and "off" position contact element at 168. The timer section D also includes the tripping solenoid 85 for operating the tripping latch, and pilot lamp 170 for indicating completion of the heating cycle.

The timer circuit is traced from the sequence selector switch 148 through parallel lines 171 and 172, including timer solenoids 151 and 161 respectively, to the main line 112. To maintain power after opening of sequence switch 148, taps are made at 173 and 174 on lines 171 and 172 respectively at points between the sequence switch 148 and solenoid coils 151 and 161 respectively, these tap lines leading through the timer switches 153 and 163 respectively and a common return line 175 to the tap point 144 between B and C section. Line 175 also supplies power to the timer switch arms 156 and 166. The timer on-relay coils 154 and 164 are connected to the main line 112 and to points intermediate the "on" timer contacts 157 and 167 and the corresponding motor. The tripping solenoid 85 connects to the main line 112 and to the "off" timer contact elements 158 and 168.

Associated with timer section D is the main contactor relay 181 with heat-on pilot lamp 182 connected in parallel therewith. Circuit connections with the timer section are made by extension of timer line 175 from point 177 through load switch 7, furnace panel door switches 179 associated with various side or rear panel doors, on-relay timer switches 165 and 155 to point 180 on the relay 181. Also the main line 112 is extended from point 183 through point 176 and starter switch 184 to the main relay 181. A pilot lamp 185 indicating complete insertion of the workpiece connects the power side of the panel door switches 179 with the main line 112.

The high-frequency section E includes the main contactor relay switches and a rectifying circuit for supplying direct current for operation of the high-frequency contactor operating coil. There are two main contactor relay switches 190, 191 and the previously mentioned switch 127 in the starter section B, also operated by the relay 181.

The rectifying circuit is made as a conventional bridge 192 and is comprised in the four branches 193, 194, 195 and 196 with copper oxide or equivalent elements inserted, one in each branch, with such polarity as to produce a direct current potential at points 197 and 198, as indicated. Alternating current is led to points 199 and 200 on the rectifier from main line 112 at 176 and from the C-D circuit 175 at point 201, the resultant tap line including in series a resistance cut-in combination of a resistance 202 and normally closed by-pass switch 203 on the resistance, and the main contactor relay switch 191. The rectified circuit connects in series the main contactor relay switch 190 and the high-frequency contactor operating coil 204. Energization of magnet coil 204 closes the switch 205 of the high-frequency high-voltage circuit 206 including the power source 207, capacitor 208 and heating coil 75

17. Usually the power source provides current at about 800 volts and 3000 cycles in the heating circuit.

Having in mind the complete organization with associated electrical and mechanical features, the operation of the furnace control follows. The side and rear panel doors are closed, closing door switches 179. The water cooling system is turned on, this resulting in closure of pressure switch 117 and flow switch 141. The main switches 115 are then closed, current flow being indicated by the various current flow indicating lamps 116, 118 and 136. Illumination of lamp 136 indicates a closed circuit through anti-reset relay 129, by way of normally closed load switch elements 101b and 8b. Simultaneously, anti-reset relay switches 131 and 132 are closed, thus locking the anti-reset relay, closing and conditioning the circuits for application of voltage on the starter section B and the timer section D on introduction of the workpiece.

The workpiece is now inserted in the furnace chamber causing the closure of load switch element 161a and thereby applying voltage to point 144 and starter section B and timer section D.

Before the workpiece has passed completely over load switch element 161a it engages the ejector rod, thus actuating the arm of load switch 8. This switch has two circuit contact elements 8a and 8b which are simultaneously actuated, normally open switch element 8a serving on closure to maintain a voltage on the starting and timing circuits irrespective of the action of load switch 101. Opening of either or both 8b or 101b shifts the anti-reset relay circuit entirely through anti-reset relay switch 131, so that should the power be withdrawn from this relay permitting opening of the switch 131, it cannot again be closed unless both load switch contact elements 8b and 101b are closed, this requiring complete unloading of the furnace.

The workpiece is now moved to the rear end of the furnace chamber closing load switch 7 in the timer D section. The starter button 42 is now pushed in bringing about closure successively of starter switches 125, 124 and 184, the closure of switch 124 being momentary. On the closure of switches 125 and 124, a closed circuit is at once established through normally closed main contactor relay switch 127 and the pilot contactor relay 121 with its associated lamp 126. Thereupon the two pilot contactor relay switches 122 and 123 are closed, switch 123 locking the pilot relay 121 closed since starter switch 124 is closed only momentarily during the hood closing movement. Also power is applied by way of switch 122 to the sequence switch 148.

The system of circuits is now conditioned for initiation of a heating cycle. This will develop when the sequence switch 148 which controls the sequence of power application in the furnace bank establishes a closed circuit to the timer section D. When this occurs timer solenoids 151 and 161 are energized, locking switches 153 and 163 are closed, timer switch arms 156 and 166 move to on-position at contact elements 157 and 167 respectively and motors 152 and 162 function to start the timing cycle. Simultaneously on-position relays 154 and 164 are energized, closing on-relay switches 155 and 165, and since load switch 7, panel door switches 179 and starter switch 184 are already closed, power is at once supplied from circuit point 144 between sections B and C through line 175, and from main line 112 to the

main contactor relay 181 and its associated signal lamp 182.

The energization of relay 181 closes main contactor control relay switches 190 and 191, and opens switch 127 in the starting section circuit. 5 The effect of opening switch 127 is to de-energize pilot contactor coil 121 and cause the opening of pilot contactor relay switches 122 and 123, thus breaking the circuit through the sequence switch. Additionally, closure of main contactor relay switch 191 closes a circuit from point 201 on power line 175 through the resistance cut-in switch 203 to point 199 on the rectifier 192, thus, applying a voltage at point 200 from main line 112, creating a direct current voltage at points 197 and 198 which is effective through closed switch 190 to energize the high-frequency contactor coil 204. Thereupon, the switch 205 in the main induction heating coil circuit is closed and power from the source 207 is applied to heating coil 17.

On completion of the heating cycle either timer switch contact arm 156 or 166 breaks contact at elements 157 or 167 and opens relay switches 155 and 165, thus disconnecting relay 181 and opening the main circuit and stopping the application of power. In addition, timer switch contact arms 156 and 166 engage contact elements 158 and 168 causing functioning of tripping solenoid 85 to open the clamping bars 27 and starter switches 125 and 184. The workpiece may now be removed from the furnace by actuating of the foot pedal and/or application of tongs.

From the description of the structure and of the electrical circuit and connections as hereinabove made, the particular utility of the invention may now be apparent. Operation of the push button 42 to the latching point opens the valve 41 to permit air under pressure to enter the closure cylinders 24 and at the same time introduce pressure to the switch 184 to make possible energization of the main contactor relay 181 and consequent activation of the power source control relay 204. Switch 125 is closed just prior to the latching of the button so that in the latched position this switch remains closed, continued pressure on the button causing overtravel of the flange 67 to close switch 124. When pressure on the button is released it returns part way to the latched position, opening switch 124 whose action is thus termed "momentary." It is pointed out that these three switches are closed in time sequence. It is also noted that the functioning of switch 184 is fully dependent upon the application of pressure to the holding cylinders 24. However, due to the fact that the holding means involve fluid pressure with its yieldable characteristics it is also apparent that the functioning of switch 184 is not dependent upon the degree of movement of the workpiece-engaging rollers 31 so that switch 184 functions irrespective of the size of the workpiece inserted in the feed opening. This relationship also permits the heating of a workpiece of such length as to extend outwardly appreciably beyond the rollers 31, in which position the rollers are spaced from each other by the inter-position of the workpiece. It is pointed out further that in the case of a long workpiece which is being subjected to a heating treatment it may be possible to remove the workpiece before the heating cycle is completed but that, if such removal is made, the piece is effectively grounded until it is well outside of the machine and the chances of its making electrical

contact with any part of the furnace with consequent damage is remote.

The particular structure shown and described for accomplishing the objects of the invention have been found to be efficacious and usable. However, it is apparent that modifications of the invention as described may be made to meet special conditions of use and hence I do not desire to be limited to the specific illustrated means except in so far as required by the scope of the claims as hereto appended.

What is claimed is:

1. In induction heating apparatus, a heating coil having a feed opening for insertion of a workpiece, a power source, a circuit including said source and coil, a relay circuit controlling the functioning of said circuit, including a relay switch, closure means for closing said coil feed opening, and single means for closing said relay switch and closure means, said closure means being adjustable independently of said relay switch.

2. In induction heating apparatus, a heating coil having a feed opening for insertion of a workpiece, a power source for supplying power to said coil, fluid pressure means laterally movable relative to the coil axis to form a yieldable feed opening closure adjustable to workpieces of different diameter, said means having pressure release mechanism and means operably connected with said closure means but capable of movement independently thereof for controlling said fluid pressure means.

3. In induction heating apparatus, a heating coil having a feed opening for insertion of a workpiece, a power source and circuit including a switch for supplying current to said coil, a control circuit including a fluid pressure operated switch and means for closing said power circuit switch, closure means for the coil feed opening, said closure means comprising two opposed, linearly movable closure elements, and fluid pressure means for closing said control circuit switch and closure elements.

4. In induction heating apparatus, a heating coil having a feed opening for insertion of a workpiece, a power source, a circuit including said source and coil, a relay circuit controlling the functioning of said circuit, including a relay switch, a starter switch and circuit operatively connected to said relay circuit to permit energization of the relay circuit and relay switch, closure means for closing said coil feed opening, and single means for closing said starter switch, relay switch and closure means.

5. In induction heating apparatus, a heating coil having a feed opening for insertion of a workpiece, a power source, a circuit including said source and coil, a relay circuit controlling the functioning of said circuit, including a relay switch, a starter switch and circuit operatively connected to said relay circuit to permit energization of the relay circuit and relay switch, closure means for closing said coil feed opening, single means for closing said starter switch, relay switch and closure means, means for establishing a heating cycle in said heating coil on closure of said starting switch, and means for disconnecting said starting switch, relay switch and closure means on completion of said heating cycle.

6. In induction heating apparatus, a heating coil having a feed opening for insertion of a workpiece, a power source, a circuit including said source and coil, starting means for initiating

11

a heating cycle in said circuit, closure means for said coil feed opening, and single means for energizing successively said starting and closure means.

7. In induction heating apparatus, a heating coil having a feed opening for insertion of a workpiece, a power source, a circuit including said source and coil, starting means for initiating a heating cycle in said circuit, closure means for said coil feed opening, single means for activating said starting and closure means, and automatic timing means for bringing about deenergization of the starting and closure means on completion of the heating cycle.

8. In induction heating apparatus, a heating coil having a feed opening for insertion of a workpiece, a power source, a circuit including said source and coil, starting means for initiating a heating cycle in said circuit, closure means for said coil feed opening, and single means for activating said starting and closure means, said starting means including a device for restoring said single means to pre-actuating position.

9. In induction heating apparatus, a heating coil having a feed opening for insertion of a workpiece, a power source, and control circuit connected to said source and coil, and closure means for closing said coil opening effective only upon energization of said control means, said closure means forming a ground connection to the workpiece.

10. In induction heating apparatus, a heating coil having a feed opening for insertion of a workpiece, a power source for supplying current to said coil, a circuit between said coil and source, a relay switch in said circuit, a control circuit including a starting switch and a relay coil for initiating a heating cycle in said heating coil by closure of said relay switch, a closure means for said feed opening and means incorporated in said control circuit for activating said closure means on closure of the starting switch and releasing said closure means at the end of the cycle.

11. In induction heating apparatus, a heating coil having a feed opening for insertion of a workpiece, a power source for supplying current to said coil, switch means controlling current supply from said source, holding means for yieldably engaging a workpiece extending within and without said feed opening, energizable means for actuating said holding means, and movable means for energization of said energizable means and closure of said switch means, said holding means automatically moving to close said feed

12

opening only on removal of the workpiece during the period of switch closure.

12. In induction heating apparatus, a heating coil having a feed opening for insertion of a workpiece, a power source for supplying current to said coil, a control circuit for making said power source effective in said coil during a heating cycle, holding means movable laterally in relation to the coil axis into engagement with a workpiece positioned in said coil with a section thereof extending out of the feed opening, energizable means for actuating said holding means, and movable means for energization of said energizable means and control circuit, said holding means being adjustable automatically to workpieces of different diameters and operable only during the heating cycle.

13. In induction heating apparatus, a heating coil having a feed opening for insertion of a workpiece, a power source, a circuit between said source and coil including a switch, a control circuit for bringing about closure of said switch, and closure means for said coil feed opening, said control circuit including means for preventing closure of said source circuit switch until closure of the feed opening is under way.

14. The combination according to claim 13 but including additionally means for preventing release of the closure means during a heat cycle.

15. In induction heating apparatus, a heating coil having a feed opening for insertion of a workpiece, a power source for supplying current to said coil, switch means for establishing flow of current from the source to the coil, a control circuit for causing closure of said switch means, closure means for closing said coil feed opening and energizable means for actuating said closure means to close said opening, and single movable means for effecting energization of said energizable means and control circuit.

16. In induction heating apparatus, a heating coil having a feed opening for insertion of a workpiece, a power source for supplying current to said coil, switch means for establishing flow of current from the source to the coil, a control circuit for causing closure of said switch means, closure means for closing said coil feed opening and energizable means for actuating said closure means to close said opening, and single movable means for effecting energization of said energizable means and control circuit, said control circuit being dependent upon supply of power to the closure means for closure of the switch means.

HAROLD A. STRICKLAND, JR.
